US00D835177S

(12) **United States Design Patent** (10) Patent No.: **US D835,177 S**
(45) Date of Patent: **** Dec. 4, 2018**

(54) **EYEWEAR DEVICE**

(71) Applicant: **Arman Hedayat**, Windermere, FL (US)

(72) Inventor: **Arman Hedayat**, Windermere, FL (US)

(73) Assignee: **Seagoggs, Inc.**, Winter Garden, FL (US)

(**) Term: **15 Years**

(21) Appl. No.: **29/540,357**

(22) Filed: **Sep. 23, 2015**

(51) LOC (11) Cl. **16-06**

(52) U.S. Cl.

USPC **D16/312**

CLAIM

The ornamental design for an eyewear device, as shown and described.

DESCRIPTION

FIG. 1 is a top-front perspective view of an eyewear device second embodiment.

FIG. 2 is a back perspective view of an eyewear device second embodiment.

FIG. 3 is a front view of an eyewear device second embodiment.

FIG. 4 is a side view of an eyewear device second embodiment.

FIG. 5 is a side view of an eyewear device second embodiment opposite the view in FIG. 5.

FIG. 6 is a top view of an eyewear device second embodiment; and,

FIG. 7 is a bottom view of an eyewear device second embodiment.

The broken lines shown in the drawings are included for the purpose of illustrating unclaimed portions of the eyewear device and forms no part of the claimed design.

1 Claim, 4 Drawing Sheets
